REFLECTOR OR BULB SHIFTING MECHANISM FOR HEAD LAMPS

Clarence A. Michel and Scott R. Conwell, Anderson, Ind., assignors to General Motors Corporation, Detroit, Mich., a corporation of Delaware

Application October 12, 1934, Serial No. 748,042

7 Claims. (Cl. 240—44)

This invention has to do with mechanism for use either in tilting a reflector in a headlamp or a bulb in a reflector in order to change the direction of the projected rays. The mechanism is especially adapted to make step by step adjustment of the reflector or bulb. In the preferred form of the invention a spring is employed to yieldingly urge the bulb or reflector in one direction and an eccentric is provided for urging it in the other direction, the eccentric preferably being operated step by step by means of a ratchet actuated by an electromagnet or, if preferred, by engine suction.

Another feature of our invention consists in combining with the tilting mechanism an adjustment to enable the initial setting of the bulb or reflector to be varied as may be desired.

The design is characterized by simplicity and economy of parts so that it is well adapted for large scale production.

Figure 1 is a section through a portion of an automobile headlamp showing our bulb tilting mechanism with parts broken away.

Figure 2 is a perspective view of the tilting mechanism of Figure 1 looking at the rear of the reflector.

Figure 3 is a section on line 3—3 of Figure 1.

Figures 4 and 5 are details, the first showing the combined eccentric and ratchet wheel, and the second showing the ratchet.

Figure 6 is a fragmentary side elevation of a modified form of tilting mechanism.

Figure 7 is a section on line 7—7 of Figure 6.

Figure 8 is a view of the elevation of the combined eccentric and ratchet wheel looking from the side bearing the eccentric.

Figure 9 is a view corresponding to Figure 1 showing a further modification in which the position of the entire tilting mechanism, bulb and socket may be adjusted.

Figure 10 is a fragmentary rear view of the mechanism of Figure 9.

Figure 11 is a fragmentary side elevation with parts in section showing suction operated mechanism for adjusting the position of the bulb, this being a modification of the construction shown in Figure 9.

Figure 12 is a rear view of the construction of Figure 11.

Figure 13 is a perspective view of the bracket carrying the bulb tilting mechanism.

Figure 14 is a view corresponding to Figure 1 showing a further modification in which the reflector is tilted along with the bulb and socket.

Figure 15 is a section on lines 15—15 of Figure 14.

Figure 16 is a fragmentary section on line 16—16 of Figure 14.

Figure 17 is a fragmentary rear view of a portion of the reflector of Figure 14.

Figure 18 is a view corresponding to Figure 1 showing the application of the invention to another form of tilting reflector.

Figure 19 is a fragmentary section on line 19—19 of Figure 18.

Figure 20 is a view taken on line 20—20 of Figure 18.

In the form shown in Figures 1 to 5 the reflector 10 is fixed, while the socket carrying the bulb is pivoted thereto. To the rear of the reflector is secured stamping 12 which is apertured to receive the lamp socket 14. The lamp socket is provided with outwardly bent lugs 16 received in sockets in the stamping 12 or in the reflector if preferred, thereby providing a pivotal mounting. A helical spring 18 arranged in the form of a ring is engaged behind a lug 20 pressed out of the top of the socket 14 and passes forwardly of lugs 22 likewise pressed out of the socket and the bottom of spring engages under hook 24 pressed out of stamping 12. Spring 18 is normally under tension and as a consequence tends to contract and wedge between lugs 22 and the back of stamping 12 thereby drawing the socket rearwardly so that lugs 16 are yieldingly held in their sockets. The purpose of lug 20 is to hold the spring 18 at a distance from the fulcrum so that when the bulb is tilted upwardly the spring is put under additional tension.

The rear end of stamping 12 is in the form of a U, and provides support for fixed pivot 26. Upon a reduced portion of pivot 26 is journaled the combined ratchet wheel and eccentric 28. The periphery of the member 28 is in the form of an eccentric engaging the rear end of the socket so that by rotating the eccentric the socket is tilted up or down. The rearward face of the member 28 is provided with an annular series of ratchet teeth 30 adapted to be engaged by tooth 32 formed on ratchet lever 34 journaled on pin 26 alongside the member 28. Coil spring 36 on pin 26 yieldingly urges the lever into engagement with the member 28. The opposite end of ratchet lever 34 has a pin and slot connection with the armature 40 of electromagnet 42 preferably clamped to the bottom of the U-shaped portion of the stamping 12.

To prevent return movement of the eccentric we may provide a spring detent such as indicated at 46 which may be mounted at one end of the pivot 26 as best shown in Figure 2.

One end of the coil of the electromagnet 42 is suitably grounded while the other end is provided with an insulated lead, best shown in Figure 1, which may be connected by suitable means 5 to a switch within reach of the operator of the car. This switch should be of such design so that upon giving it one unit of movement the circuit through the electromagnet is momentarily closed, pulling down armature 40, swinging 10 ratchet lever 34 and rotating the combined ratchet wheel and eccentric 28 through one or more notches, depending on the design of the ratchet lever. This will result in tilting the rear end of the lamp socket 14 either up or down, depending 15 upon the position of the eccentric. Spring 18 at all times acts to hold the socket against the eccentric. By operating the switch a number of times the socket may be tilted up or down to the desired extent within the range 20 of movement made possible by the design of the eccentric. It will be apparent that this form of the invention, as with all the others, the wiring of the tilting mechanism may be such that the bulbs in the two headlamps may move up 25 and down together upon manipulation of the switch, or if desired separate switches could be provided for each headlamp. If a single switch is preferred, it is also possible to arrange the wiring and the synchronizing of the tilting mechanism 30 so that as one bulb is tilted up the other is tilted down, or if preferred they may be arranged less than 180° out of phase. All of this is a matter of choice in securing such combinations of beam patterns as may be desired.

We have also illustrated in Figure 1 a conventional two filament bulb. Such bulbs are usually 35 so wired as to permit independent energization of the filaments to obtain various beam combinations. Obviously, the switch or switches employed 40 for determining combination of filaments used may be combined with the switch for controlling the energization of the magnets to get such combinations of filament positioning as may be desired. However, it is to be expected that 45 the tilting mechanism herein disclosed will find its greatest use with bulbs containing but a single filament.

In Figures 6 to 8 we have shown a slight modification in that there is mounted on the pivot 26' 50 a socket actuator 50 having a forked upper end provided with lugs 52 engaging in apertures 54 provided at opposite sides of the socket 14'. The opposite end of actuator 50 is apertured and provided with inwardly projecting lugs 55 adapted 55 to ride on the periphery of eccentric 58 formed on ratchet wheel 60. Obviously, when the ratchet wheel is rotated the eccentric moves the bulb up and down through actuator 50. The remaining details of the construction are the same as previously described.

In Figures 9 and 10 we have shown a further development of the invention in which provision is made for initial adjustment of the setting of the bulb. From such setting the solenoid mechanism provides as before for the step by step 65 adjustments normally made use of in the operation of the vehicle. Here the stamping 62 is of somewhat different shape from the corresponding part 12 of the form shown in Figure 1, being provided 70 with outwardly extending arms equipped with pivots 64 on which is swung stamping 66 carrying electromagnet 68 having its plunger 70 pivoted to ratchet 72 which actuates eccentric 74 in the manner previously described to cause the 75 bulb socket to pivot about its fulcrum (not

shown) in the stamping 62, this fulcrum being the same as that shown in Figures 1 and 3. The upward movement of the rear end of the bulb socket is, as before, resisted by spring 78. It will be understood that the pivots 64 and the fulcrum 5 of the bulb socket are in alignment so that the stamping 66 and the parts carried by it, together with the lamp socket, which bears on eccentric 74, may pivot together about this common axis. The construction as so far described, except for 10 the pivotal mounting of the stamping 66, is substantially the same as previously described. To the bottom of the stamping 66 is secured a lug 80 which is connected by universal joint to a rod 82 threaded in bracket 84 secured to the lamp 15 housing. The housing is provided with an aperture at 86 to permit access to the end of the rod 82 which is slotted to permit actuation by a screw driver. Coil spring 90 encircles rod 82, bearing at one end against a suitable seat resting on bracket 84 and at the other end bearing against collar 92 secured on the lug 80. The spring 90 applies tension to the rod 82 and so tends to lock it in adjusted position.

It will be apparent that by rotating rod 82 the 25 stamping 66 and with it the bulb tilting mechanism and the socket may be tilted up or down about a horizontal axis. In any position to which these parts may be adjusted by manipulation of rod 82 the solenoid 68 is effective to 30 provide the full range of adjustment of position of the bulb made possible by the eccentric 74.

In Figures 11 to 13 we have shown a further modification in that the ratchet 94 is operated 35 by means of plunger 96 secured to diaphragm 98 urged in one direction by spring 100 and in the other direction by engine vacuum applied through tube 102 leading to the manifold or to any other 40 of the parts of the engine in which vacuum exists or through which fluid flows so as to exert an aspirating action on the pipe 102 to cause movement of the diaphragm. The construction is otherwise substantially the same as previously 45 described.

While we have not illustrated the valve mechanism for controlling application of suction to the diaphragm 98, it is obvious that this may be done in various ways, either by connecting the suction lines to suitable valves on the dash or by using remote control of the suction, operated 50 either electrically or mechanically.

The bulb tilting mechanisms here described may be applied to tilt the reflector with its bulb instead of the bulb alone, and in Figures 14 to 17 55 we have shown such an arrangement. The reflector 110 is equipped with the usual bulb mounted in socket 112 secured to the reflector in any desired manner. In this form of the invention as well as in the others the bulb may contain a single filament or independently energizable filaments as in conventional headlamps. To the opposite sides of the reflector 110 is secured a strap 114 carrying trunnions 116. These trunnions are received in sockets provided in stampings 118 fastened in any suitable manner to the headlamp 60 housing. On the strap 114 is mounted solenoid 120 provided with armature 122 operating the ratchet 124 which, through a suitable ratchet wheel, not shown, actuates eccentric 128 engaging adjustable abutment 130 pivoted at 132 to 70 bracket 134 rigidly secured to the lamp housing. An adjusting rod 136 has one end received in socket in member 130 and the other end threaded in member 134. The exposed slotted end of rod 136 is accessible through opening 138 in the head- 75

lamp housing. Spring 140 arranged between the member 134 and the reflector yieldingly urges the reflector and its connected parts in a direction to maintain the eccentric 128 in engagement with the adjustable abutment 130.

It will be apparent that by adjusting the rod 136 the abutment 130 is swung about its pivot and through its engagement with eccentric 128 swings the assembly consisting of the adjusting mechanism, strap 114 and reflector about the axis of trunnions 116, thereby tilting the reflector upwardly or downwardly as desired. In any position of adjustment of rod 136 the eccentric 128 may be actuated by the electromagnet 120 to effect the desired adjustment of the reflector. It will be obvious, of course, that instead of the electromagnet the suction operated ratchet actuator of Figure 11 may be employed.

In the form shown in Figures 18 to 20, 144 indicates the reflector which is supported on the in-turned flange 146 of the lamp housing 148 by means of supporting screws 150 having their heads countersunk in the flange and provided with compression springs 152 encircling their shanks and urging the reflector away from the flange, as described in pending application S. N. 723,833, filed May 4, 1934, Mead and Michel. At least two such adjusting screws are provided, preferably located at opposite ends of horizontal diameter. In addition, a third adjusting screw may be provided at the top of the lamp. By rotating these screws the reflector may be tilted or moved inwardly or outwardly as desired. The arrangement also permits rocking of the reflector about the seat of the head of the screw as a pivot. The screws thus provide a pivotal mounting for the reflector.

To the bottom of the reflector is secured a stamping 153 which strengthens the reflector flange at this point, and provides a seat for spring 154, bearing at its other end against a suitable seat in the housing flange 146. Against the other side of the stamping 153 bears an eccentric 156 having its upper surface provided with ratchet teeth as in the previous form of the invention. Eccentric 156 has an axial extension 158 formed at its outer end with flat sides to permit manipulation. Extension 158 is received in an aperture in a U-stamping 160 supported by U-shaped bracket 162, secured to the lamp housing. Stud 164 threaded in the upper arm of the U-shaped stamping 160 has its lower end piloted in eccentric 156 and serves as a journal for the ratchet 166. As in the previous forms of the invention, ratchet 166 is connected to armature 168 of an electromagnet 170 mounted on bracket 172 riveted to the lamp housing in any suitable manner. One end of the winding of the electromagnet 170 is secured as shown to terminal 174 insulated from bracket 172, and from the terminal extends a suitable lead going to the control.

It will be apparent that in this form of the invention, as in the others, energization of the solenoid 170 will operate the ratchet mechanism, and so rotate the eccentric 156 as to either tilt the reflector upwardly or tilt it downwardly, spring 154 causing the bottom of the reflector to follow the eccentric. The advantage of having the extension 158 on the eccentric projecting through the hole in the lamp housing is that this makes it possible to initially adjust the two headlamps so that they will tilt up and down in unison when the electromagnets are actuated from the switch at the driver's seat. Of course, if desired, the

lamps may be adjusted so that they move the reflectors out of step with each other.

In the last described form of the invention we have shown at 176 a contact carrier for bulb 178 which may be of the type having a pre-focused base. However, any suitable bulb mounting may be employed.

We claim:

1. In a headlamp a light source, means for mounting the light source for adjustment within the headlamp, means for shifting the position of the light source comprising a cam, spring means for resiliently holding the light source mounting in engagement with the cam, step by step means for actuating the cam, a pivotal mounting for said light source shifting means, and means for adjusting the position of said last-named mounting comprising an adjustable thrust member having one end engaging the mounting and the other end accessible for manipulation from outside of the headlamp.

2. In a headlamp a light source, means for mounting the light source for pivotal movement within the headlamp, means for shifting the position of said light source, a pivoted support for said last-named means, said support being in addition to the pivotal mounting for the light source and having its pivotal axis coincident with the axis of pivotal movement of the light source, and means for adjusting the position of said pivoted support.

3. In an adjusting mechanism for headlamps and the like the combination of a support, a bracket mounted thereon having a U-shaped portion, a shaft extending between the legs of the U, an eccentric on the shaft, a ratchet wheel secured to the eccentric, a lever mounted on the shaft having a pawl in engagement with the ratchet wheel, a torsion spring on the shaft engaging the bracket and urging the lever in one direction, means mounted connected to the lever for intermittently actuating the lever to give step by step movement to the ratchet wheel and, a light source pivotally mounted on the support and arranged to be actuated by the eccentric to effect tilting thereof.

4. The combination of a headlamp having a reflector therein, a lamp socket pivoted in the reflector, a lamp in the socket, a support secured to the reflector, a shaft on the support, an eccentric on the shaft engaging the socket to tilt the same, a ratchet wheel secured to the eccentric, a lever mounted on the shaft having a pawl in engagement with the ratchet wheel, a torsion spring on the shaft engaging the bracket and urging the lever in one direction, a motor device having a driven element operatively connected to the lever, and means for energizing the motor device to produce step by step movement of the socket.

5. The combination of a headlamp housing having a reflector therein, a lamp socket pivoted in the reflector, a lamp in the socket, a support pivotally secured to the reflector on an axis aligned with the axis of pivotal movement of the socket, means carried by the support and operatively connected to the socket for effecting step by step pivotal movement of the socket, and means connecting the housing and the pivoted support for adjusting the position of the last-named means and the socket.

6. The combination of a headlamp housing having a reflector therein, a lamp socket pivoted in the reflector, a lamp in the socket, a support pivotally secured to the reflector on an axis

aligned with the axis of pivotal movement of the socket, a shaft on the support, an eccentric on the shaft engaging the socket to tilt the same, a ratchet wheel secured to the eccentric, a lever mounted on the shaft having a pawl in engagement with the ratchet wheel, a torsion spring on the shaft engaging the bracket and urging the lever in one direction, means on the bracket operatively connected to the lever and adapted to produce step by step movement thereof to correspondingly adjust the socket, and means con-

necting the housing and the pivoted support for adjusting the position of the last-named means and the socket.

7. In the combination as defined in claim 6, said last-named means comprising a rod pivoted to the support and having threaded engagement with the housing, and a spring yieldingly urging the support away from the rod. 5

CLARENCE A. MICHEL. 10
SCOTT R. CONWELL.
